UNITED STATES PATENT OFFICE.

ROBERT L. LYONS, OF WALTHAM, MASSACHUSETTS.

BUTTON-SEWING MACHINE.

961,508.

Specification of Letters Patent. Patented June 14, 1910.

Application filed September 10, 1906. Serial No. 333,940.

To all whom it may concern:

Be it known that I, ROBERT L. LYONS, of Waltham, in the county of Middlesex, State of Massachusetts, have invented certain new and useful Improvements in Button-Sewing Machines; and I hereby declare that the following is a full, clear, and exact description of the same, reference being had to the accompanying drawings, forming part of this specification.

This invention has reference to improvements in button sewing machines adapted to sew buttons to an underlying fabric through button holes formed in a superposed fabric.

One object of the invention is to expand the button hole previous to the sewing operation without engaging the button hole.

Another object of the invention is to so construct a button hole sewing machine of this nature that the button holes may be expanded by devices acting on the fabric at the sides of the button hole.

Another object of the invention is to avoid the use of button hole expanding devices located, during the sewing operation, between the button and the fabric.

Another object of the invention is to so construct a button sewing machine that two overlapping layers of fabric may be held together as they are fed forward to the button sewing position so that the button may be sewed through the button hole.

The objects of the invention will appear from the following description.

The invention consists in such novel features of construction and combination of parts as shall hereinafter be more fully described and pointed out in the claim.

Figure 1, represents a side elevation of the improved button sewing machine, parts of the same being broken away. Fig. 2, represents a plan view thereof. Fig. 3, represents a bottom plan view of parts of the same. Fig. 4, represents a partial section taken on line 4-4 Fig. 5. Fig. 5, represents an end view of the machine. Fig. 6, represents a plan view of portions of the button clamp and the button hole expander with a button hole expanded thereby. Fig. 7, represents a front view of the button clamp in the raised position, showing the two layers of cloth in position thereunder. Fig. 8, represents a diagrammatic view illustrating the means for holding the two edges of a garment together during the button

sewing operation. Fig. 9, represents a plan view of the same to more clearly show the manner in which the edge portions of a garment, or other overlapping fabrics on 60 which buttons are to be sewed, are stretched between the button clamp and the tension device whereby the dragging sidewise of these edges by the weight of the garment is prevented.

65

Similar characters of reference designate corresponding parts throughout.

As shown in the drawings 10 represents the bed plate of the machine having the standard 11 furnished with the arm 12 and 70 the head 13. This bed plate 10 at the end opposite to that from which the standard 11 extends is furnished with the channel 14, of any desired length, which separates the button clamp supporting arm 15 of said bed 75 plate from the work supporting member 16 of the bed plate having the usual needle passage. From the arm 15 depends the web 17 and from the work support 16 depend the webs 18 and 19 which form the sides of a 80 chamber in which parts of the operating mechanism are contained, these webs 15 and 18-19 being primarily designed to protect the articles under operation from contact with mechanism located beneath the bed 85 plate.

In bearings of the head 13 is mounted to slide vertically the needle bar 20 having means, of any usual construction, for carrying a needle 21 and operated by means of 90 the usual shaft 22 journaled in bearings of the arm 12 and the arm 23 pivoted to a member of said shaft 22 and to a fitting on the needle bar 20. The shaft 22 is driven in any usual manner to effect the reciprocation of 95 the needle bar 20.

The gate 24 is pivotally mounted on the head 13 and has bearings in which the presser and lifter rod 25 is free to rotate and slide, the spring 26 located between a 100 portion of said gate 24 and the sleeve 27, of the laterally extending arm 28, on the rod 25, tending to move said rod toward the work support. At the free end of the gate 24 is pivoted one end of the rod 29, 105 the other end of which rod is adjustably secured by the clamp 30 working in the curved slot of the plate 31 which is secured at one end to the upper portion of the vertical shaft 32 journaled in bearings and extending through the bed plate 10.

The button clamp 34 is of the usual con-

struction except that the work supporting plate usually extending beneath the arms 35-35 is omitted and that on the arms 35-35 of said clamp are mounted out-
 5 wardly and downwardly inclined spring arms 36-36 which extend somewhat below the lower surfaces of said arms and the lower ends of which are designed to engage a fabric placed thereunder and to exert a
 10 spreading action on said fabric when the button clamp is moved downward. This button clamp is pivotally connected with the presser and lifter rod 25 to move upward and downward, and laterally therewith to
 15 follow the movement of the gate 24. This lateral movement is permitted by reason of the width of the guide 39 mounted on the arm 15 as said guide is considerably wider than the block 40, slideable in said guide, to
 20 which the rear portion of the button clamp is pivoted. Any ordinary means herein shown as the arm 41 pivotally mounted on the head 13 and engaging under one end of the arm 28 on the presser rod 25 is used to
 25 lift the forward end of the button clamp at times to permit of the positioning of the fabric thereunder.

At the under side of the bed plate 10 is journaled the main shaft 42 which is furnished with the worm gears 43 and 44 any ordinary mechanism for driving this shaft 42 is utilized. Motion is transmitted from the shaft 42 by means of the gears 45 and 46 to the looper shaft 47, journaled in bearings beneath the work support 16, and furnished with the looper hook 48.

Extending from the lower portion of the bed plate 10 is the stud 49 on which the gear 50 and the cam 51 are journaled to rotate together, the gear 50 meshes with the worm 43 of the shaft 42 and the cam 51 works against one end of the lever 52 pivotally mounted at the under side of the bed plate, the other end of this lever 52 engages
 45 the arm 53 extending from the shaft 54, journaled in bearings beneath the button clamp support arm 15, and having the crank arm 56 the pin 57 of which is engaged in a transverse bearing in the block 40 whereby
 50 back and forth movement of the block 40 and the button clamp 34, connected therewith is effected, such back and forth movement being controlled by the shape of the cam 51 which shape is determined by proposed number of stitches in each group of stitches. Pressure is exerted by the spring 54', secured to the shaft 54 and bearing against the bed plate 10 to resist the rotation
 55 of said shaft and to hold the end of the lever 52 against the cam 51.

From the under side of the bed plate 10, adjacent the worm 44 of the shaft 42 extends the stud 58 on which is journaled the gear 59 meshing with the worm 44 and having the cam 60 which works against the pin 61 of

the crank arm 62 fixed at the lower end of the vertical shaft 32 to effect the partial rotation of said shaft and the swinging of the plate 31 on its pivot whereby the rod 29 is caused to draw the free end of the gate 24 toward the head 13 against the action of the spring 13' on said head and bearing against a part of said gate. When the recess 63 of the cam 60 is brought opposite the pin 61 movement of said pin is permitted 75 to allow the spring 13' to force the free end of the gate 24 outward from the head 13.

The clamp 65 is designed to engage the neck portion of a garment as shown in Figs. 8 and 9 and to this clamp is fixed a flexible belt 66 which works over a pulley 67, of any usual construction and mounting, and having a weight 68 which exerts a drawing strain on the garment or work to hold the edges A and B in the overlapping 85 position shown and to stretch these edge portions flat from that portion held downward by the arms of the button clamp, preferably, to the end of the garment thus keeping the edges overlapping against the lateral 90 strain of the weight of the garment.

In the operation of the machine two layers, A and B of cloth, in the upper layer A of which a button hole has previously been formed, are placed upon the plate 10, the 95 button hole C being located beneath the ends of the button clamp arms 35-35 and a button D is placed in position in said arms; the button clamp is now brought downward and, in this movement the spring engaging devices 36-36 are brought into engagement 100 with the upper layer A of the fabric, the continued downward movement of the button clamp then effecting the spreading action of the lower ends of said springs 36-36 105 to stretch said upper layer in a direction at right angles to the button hole C as is shown in Fig. 6 of the drawings and to expand the button hole. The button sewing operation now proceeds until the button is sewed to the layer B by stitches passing through the expanded button hole. When the lever arm 41 is operated to lift the button clamp the spreading springs 36-36 automatically disengage from the layer A and the layers A 110 and B are free to be fed forward to position another button hole.

The tension device herein shown is of simple construction but I do not wish to limit myself to any particular construction in this 120 device as I am aware that various modified forms may be used for the purpose herein set forth.

It is noticed that the button hole need not be accurately positioned except as regards 125 registration with the button to permit the sewing stitches to pass through the button hole when expanded as the button hole will be expanded if placed at any point between the ends of the springs 36-36.

It is evident that the structure of the button hole expanding means may be varied from that herein shown without departing from the spirit of this invention.

5 Having thus described my invention, I claim as new and desire to secure by Letters Patent.

In a button sewing machine the combination with means for supporting two layers 10 of fabric the upper of which has button holes, and yielding means adapted to exert a tension on said layers approximately in line with the button holes, of a button clamp movable toward and from said fabric sup-

port, button sewing means, and fabric 15 spreading means carried by the button clamp and acting when engaged with the upper fabric to spread the same and to expand one of the button holes therein over the tensioned lower layer as and for the purpose 20 described.

In testimony whereof I affix my signature in presence of two witnesses.

ROBERT L. LYONS.
